UNITED STATES PATENT OFFICE.

JOSIAH L. MERRILL, OF PITTSBURGH, PENNSYLVANIA, ASSIGNOR TO THE GENERAL REFRIGERATION CO., A CORPORATION OF OHIO.

EXPANSION-VALVE.

1,262,823.

Specification of Letters Patent. Patented Apr. 16, 1918.

Application filed December 21, 1910. Serial No. 598,544.

To all whom it may concern:

- Be it known that I, JOSIAH L. MERRILL, a citizen of the United States, residing at Pittsburgh, county of Allegheny, State of Pennsylvania, have invented certain new and useful Improvements in Expansion-Valves, the following being a full, clear, and exact disclosure of the one form of my invention which I at present deem preferable.
- 10 For a detailed description of the present form of my invention, reference may be had to the following specification and the accompanying drawing, which shows my valve partly in section.
- 15 My invention relates to valves employed to allow the passage, from a compression chamber into a space of lower pressure, of a gas such as anhydrous ammonia or other gas employed, for example, in refrigerating 20 apparatus.

The usual practice in such valves has been to form the small opening through which the gas flows in a disk of comparatively thin metal, the result being that it is difficult to expand the gas down to a very low pressure, because on the outlet side there is formed in the disk a zone or circle of chilled metal surrounding the opening but at a slight radial distance from the opening 25 itself. This zone of chilled metal cuts off the transmission of heat through the metal of the disk to the edges of the opening and the opening becomes wholly or partly closed by frost and ice in the course of any long 30 continued operation. It is my intent to provide a valve for the expansion of smaller amounts of material than has heretofore been possible in continuous operation. To that end I form the valve opening as a duct 35 of considerable length through metal of a thickness, measured along the duct, greater than the penetrating effect of the chill produced by the expanding gas on the outlet side of the duct. Moreover, I give this duct 40 a gradually increasing area from its inner to its outer end. By this means I distribute the refrigerating effect along the length of the duct. This also serves to convert the pressure of the gas into velocity on the 45 principle of the expanding nozzle in a steam turbine. This tends to produce a blast which will dissipate any particles of ice or frost that tend to form and prevent their accumulation in or around the extremity of the duct. There is also a smooth 50 55

and gradually enlarging passageway from the orifice outward which tends to prevent local eddies in the outward flow of the stream such as might result if the space were of pocket form, or had subsequent restrictions or internally projecting shoulders. Such eddies would tend to concentrate the chilling effect on the walls near to the needle aperture.

Referring to the drawing, A represents 60 the body of my valve. B is an interior bushing seated against a shoulder in the bore of the valve and forming a nut for the screw of the adjusting needle C. Back of the bushing is a washer D and back of the 65 washer is the space for the usual packing, held in place by nut E. The gas enters the valve by a passage G.

At the extremity of body A is a projection F in which is formed the escape opening 70 for the gas in the form of a duct H passing through the projection F and flared or enlarged toward its outlet end. Through this duct H the high-pressure gas in the body of the valve is allowed to escape into 75 the low pressure space outside. The expansion of the gas will begin at the entrance to the duct and will continue as it passes through the duct in proportion to the enlargement in its cross area. This will 80 distribute the chilling or refrigerating effect of the expansion along the entire length of the duct and prevent its concentration at a particular point. At the same time the 85 mass of metal around the duct is of such 90 length that the external chill around the opening will not penetrate back along the duct far enough to cut off the conductivity of the metal around the throat of the duct. From this it will be seen that the pressure 95 on the fluid entering the passage G is converted into velocity as said fluid passes through the duct H, the velocity of the gases carrying the frosting point well beyond the valve. It will be noted that the taper of 100 the duct H is so proportioned to the length of the duct that the maximum expansion of the fluid is obtained at the rear extremity thereof.

What I claim as new and desire to secure 105 by Letters Patent is:

1. An expansion valve for refrigerating systems comprising a body having an inlet passage and an outlet duct communicating with said passage through a minute orifice,

the size of which is definitely proportioned to the size of the inlet passage to maintain pressure in the latter, said outlet duct being elongated and flaring from said orifice 5 whereby the frosting point is carried beyond the valve by the velocity of the refrigerating gas, the thickness of the metal, measuring along the duct, being greater than the penetrating effect of the chill produced by the eddying back of the expanding gas on the outlet side of the duct against the surrounding metal, and a valve controlling said orifice.

2. An expansion valve for refrigerating systems comprising a body having an inlet passage and an outlet duct communicating with said passage through a minute orifice, the size of which is definitely proportioned to the size of the inlet passage to maintain pressure in the latter, 15

said body being provided with an extension through which the outlet duct extends longitudinally, the outlet duct being elongated and flaring from said orifice, whereby the frosting point is carried beyond the valve 25 by the velocity of the refrigerating gas, the thickness of the metal, measuring along the duct, being greater than the penetrating effect of the chill produced by the eddying back of the expanding gas on the outlet 30 side of the duct against the surrounding metal, and a valve controlling said orifice.

In witness whereof I have hereunto set my hand, before two subscribing witnesses, this 12th day of December, 1910.

JOSIAH L. MERRILL.
